[57] **CLAIM**

We claim the ornamental design for a drawer front for modular container for media storage, as shown and described.

DESCRIPTION

FIG. 1 is a perspective view of a drawer front for modular container for media storage showing our new design, the broken lines in FIGS. 1, 3-8; 10-14 showing a drawer, locking device and modular container being for illustrative purposes only and forming no part of the claimed design; FIG. 2 is a front view thereof; FIG. 3 is a rear view thereof; FIG. 4 is a right side view thereof; FIG. 5 is a left side view thereof; FIG. 6 is a top view thereof; FIG. 7 is a bottom view; FIG. 8 is a perspective view of an alternate embodiment of the design shown in FIG. 1; FIG. 9 is a front view of FIG. 8; FIG. 10 is a rear view of FIG. 8; FIG. 11 is a right side view of FIG. 8; FIG. 12 is a left side view of FIG. 8; FIG. 13 is a top view of FIG. 8; and, FIG. 14 is a bottom view of FIG. 8.
